H. R. WEBB, JR.
SPRINGLESS RATCHET WRENCH.
APPLICATION FILED APR. 12, 1917.

1,258,382.

Patented Mar. 5, 1918.

UNITED STATES PATENT OFFICE.

HENRY RUSSELL WEBB, JR., OF EAST ORANGE, NEW JERSEY, ASSIGNOR OF ONE-HALF TO LOUIS FRED GEORGE AND ONE-FOURTH TO MORRIS STEIGLER, BOTH OF NEWARK, NEW JERSEY.

SPRINGLESS RATCHET-WRENCH.

1,258,382.

Specification of Letters Patent.

Patented Mar. 5, 1918.

Application filed April 12, 1917. Serial No. 161,640.

To all whom it may concern:

Be it known that I, HENRY RUSSELL WEBB, Jr., a citizen of the United States, and a resident of East Orange, Essex county, New Jersey, have invented a new and useful Improvement in Springless Ratchet-Wrenches, of which the following is a full, clear, and exact description.

My invention relates to improvements in ratchet wrenches, and the object of my invention is to produce a strong, simple, easily operated wrench which has a removable jaw with ratchet teeth thereon, and an oscillating handle connecting with the wrench head and provided with a tooth to engage the ratchet teeth of the jaw so that by oscillating the handle and turning the wrench, it will operate like an ordinary ratchet wrench. My invention is also intended to produce a split head with a central opening to contain the rotatable jaw, and adapted to provide for the easy removal of the jaw so that a jaw with a desired opening therein or with a die thread therein, can be applied to the wrench head or removed readily when desired. My invention is especially intended to afford a simple strong connection between the wrench head and handle.

Reference is to be had to the accompanying drawings forming a part of this specification, in which similar reference characters indicate corresponding parts in all the views.

Figure 1 is a broken side elevation partly in section of the wrench embodying my invention, the wrench being shown open.

Fig. 2 is a side elevation of a modified form of the wrench.

Fig. 3 is a cross section on the line 3—3 of Fig. 2.

Fig. 4 is a detail of the removable jaw common to the type of wrench shown in both Figs. 1 and 2, and

Fig. 5 is a cross section on the line 5—5 of Fig. 2.

The wrench has a cylindrical jaw 10 with a nut opening 11 therein, and with raised ratchet teeth 12 around its circumference. Obviously the opening 11 can be made of any suitable size or shape, and the jaw can represent a thread cutting die if desired without affecting the invention.

The jaw is carried by a split head comprising the members 13 and 14 which are

hinged together, on one side as shown at 15, and which have a central opening to receive the jaw. The meeting ends of the head members 13 and 14 can be secured in any convenient way, and I have shown the member 14 provided with a projecting lip 16 closing into a corresponding recess 17 of the opposite member.

The head members 13 and 14 have an internal channel 18 in which the ratchet teeth 12 are held, and in which they move. The head member 13 has a recess or opening 19 in its central edge portion as shown in the drawing to receive the end 20 of the handle 21, so that the handle can oscillate in the aforesaid opening, and to facilitate this operation and to form a simple and convenient connection between the head and the handle, a pin 22 is used which extends through the head member 13 and through the end portion 20 of the handle. The head or end portion 20 of the handle has at its inner edge and at one side, a rigid tooth 23 which is adapted to engage the ratchet teeth 12 of the jaw 10, and the handle member 21 is preferably, though not necessarily, provided with a wrench slot 24 at one end.

It will be noticed that this form of wrench has no spring, and it operates substantially like an ordinary ratchet wrench. The handle when oscillated in one direction will cause the tooth 23 to engage one of the teeth 12, and when the handle is turned in the right direction the jaw 10 will turn with it, and the handle can then be turned back to get a new hold. When the wrench is to be used for turning the jaw in the opposite direction it is simply turned over.

In Figs. 2, 3 and 5 I have shown a slight modification of the wrench in which the wrench is provided with head members 25 and 26 having a central opening for the jaw 10, these being hinged together and secured by a pin 27, and at the opposite ends the members 25 and 26 connect with the handle 21 by a pin which also serves the purpose of uniting the members. At this point the members are split to receive the flat end of the handle 21, and the member 25 is recessed as shown at 28 to receive the tongue 29 on the opposite member 26, while a pin 30 passes through the tongue and groove parts 28 and 29, the pin having preferably a thumb nut 29 connecting with it. The con-

nection between the handle and jaw is the same in the modified construction as in the construction shown in Fig. 1. In either case it will be seen that I have produced a very 5 simple strong springless wrench which it is hardly possible to get out of order, which can be readily operated, and in which the jaw can be easily inserted or removed.

Attention is called to the fact that in 10 the construction shown in Fig. 2 the wrench head can be swung open by moving the pin 27 so as to permit the removal of the jaw 10, and the handle can be readily removed by removing the pin 30.

15 I claim:—

1. A springless ratchet wrench comprising a split head having a central opening, an internal channel, and an opening through the head wall from the back of the channel, 20 a cylindrical jaw having raised exterior ratchet teeth running in the aforesaid channel, a handle extending into the aforesaid

opening having a single rigid tooth at its inner end and near one side to engage the teeth of the jaw, and a pivot pin serving 25 to unite the head members to the handle and as a pivot for the handle.

2. A springless ratchet wrench comprising a split head the members of which are pivoted together and have a central opening and an internal channel, also an opening from the channel through the back of one of the members, a jaw turning in the head and having external peripheral teeth to enter the aforesaid channel, and a handle pivoted in the aforesaid opening in one of the head members and provided at one side of its pivot with a single rigid tooth engaging the ratchet teeth of the jaw.

HENRY RUSSELL WEBB, JR.
